UNITED STATES PATENT OFFICE.

PETER F. SNYDER, OF DUQUESNE, PENNSYLVANIA.

PORTABLE CIRCULAR SAW.

1,057,180.

Specification of Letters Patent. Patented Mar. 25, 1913.

Application filed July 8, 1912. Serial No. 708,242.

To all whom it may concern:

Be it known that I, PETER F. SNYDER, a citizen of the United States of America, residing at Duquesne, in the county of Allegheny and State of Pennsylvania, have invented certain new and useful Improvements in Portable Circular Saws, of which the following is a specification, reference being had therein to the accompanying drawing.

This invention relates to a portable circular saw, and the objects of my invention are to provide a circular saw that can be easily and quickly shifted and adjusted whereby it can be conveniently positioned for immediate use.

Another object of this invention is to provide a saw of the above type that is motor operated and the motor used as a counterbalance for maintaining the saw in an elevated position and out of the road when not in use.

A further object of this invention is to provide a saw of the above type consisting of an inexpensive construction, novel adjustments and parts that contribute to an efficient machine for the purposes for which it is employed.

With the above and other objects in view the invention resides in the novel construction, combination and arrangement of parts to be hereinafter specifically described and then claimed.

Reference will now be had to the drawing, wherein:

Figure 1 is a front elevation of the saw, and Fig. 2 is a side elevation of the same.

Further describing my invention with reference to the drawing, wherein like numerals denote corresponding parts throughout: 1 denotes a rail and movable upon said rail is a hanger comprising triangular side frames 2 supporting revolute flanged wheels 3 adapted to move upon the rail 1. The lower ends of the frames 2 are connected by a transverse pin 4 and suspended from said pin is a link 5.

6 denotes a yoke swiveled upon the lower end of the link 5 and fulcrumed at the lower end of the yoke 6 are side arms 7. The rear ends of the arms 7 pivotally support a housing 8 for an electrically operated motor 9. The upper end of the housing 8 is pivotally connected by links 10 to

the yoke 6, said links and the arms 7 being adjustable relatively to the yoke.

11 denotes adjustable bearings carried by the outer ends of the arms 7 and mounted in said bearings is a transverse pin 12. Suspended from said pin are extensible side frames 13 having the lower ends thereof provided with bearings 14 for a transverse revolute shaft 15. One of the bearings 14 has a guard 16 for a circular saw 17 that is mounted upon one end of the shaft 15. The shaft 15 between the suspended frames 13 has a grooved sheave 18 and revolvably mounted upon the transverse pin 12 is a grooved sheave 19. Passing over the sheaves 18 and 19 are endless cables or belts 20.

21 denotes the armature shaft of the motor 9 and mounted upon said shaft is a grooved sheave 22. Passing over this sheave and the sheave 19 are endless cables or belts 23.

24 denotes a switch block carried by the suspended frames 13, said block having a handle 25 and a push button 26. The push button 26 is connected by a wire 27 to a suitable source of electrical energy, as a generator, and by a wire 28 to the motor 9. The motor 9 is connected by a wire 29 to the same source of electrical energy as the wire 27. The suspended frames 13 are reduced or increased in their longitudinal dimension by adjustable side plates 30.

The housing 8 and the motor 9 serve as a counterbalance for the frames 13 and when the saw 17 is not in use, the same is elevated and out of the road.

The operator or attendant of the saw can easily grip the handle 25, lower the saw 17, push the button 26 and set the motor in operation, whereby the saw 17 will be revolved through the medium of the endless cables or belts 20 and 23.

It is apparent from the construction just described that the saw can be swung in a horizontal plane or raised or lowered, thereby permitting the operator or attendant of the same, to conveniently use the saw in connection with a piece of work. The saw can be located upon a row of carpenter benches and shifted from one bench to another when occasion may require.

The portable saw in its entirety can be made of light and durable metal, and I would have it understood that the invention

is susceptible to such changes as fall within the scope of the appended claim.

What I claim is:—

A portable saw comprising a rail, a hanger movable thereon, a yoke swiveled relatively to said hanger, side arms fulcrumed in said yoke, a motor housing movably supported by said side arms, side frames suspended from said arms, a circular saw revolvably supported by said frames,

and an electric motor carried by said housing and adapted to impart a rotary movement to said saw.

In testimony whereof I affix my signature in the presence of two witnesses:

PETER F. SNYDER.
